Henning, Los Angeles, Calif.

Application September 3, 1953, Serial No. 26,694

Term of patent 7 years

(Cl. D85—2)

To all whom it may concern:

Be it known that we, Walter H. Henning and Eugenia Williams Henning, both citizens of the United States, residing at Los Angeles, in the county of Los Angeles and State of California, respectively, have invented a new, original, and ornamental Design for a Combined Ash Tray and Cigarette Drawer or Similar Article, of which the following is a specification, reference being had to the accompanying drawing, forming part thereof.

Fig. 1 is a perspective view of the combined ash tray and cigarette drawer or similar article embodying our new design; Fig. 2 is a view in side elevation of the same; Fig. 3 is an end view in elevation of the same taken of the remote end as depicted in Fig. 1; and Fig. 4 is a vertical section taken substantially upon the line 4—4 upon Fig. 3 in the direction indicated.

We claim:

The ornamental design for a combined ash tray and cigarette drawer or similar article, as shown.

WALTER H. HENNING.
EUGENIA WILLIAMS HENNING.
